UNITED STATES PATENT OFFICE.

CORWILL JACKSON, OF KALAMAZOO, MICHIGAN.

TAMPER.

1,329,049.

Specification of Letters Patent. Patented Jan. 27, 1920.

Application filed May 23, 1919. Serial No. 299,262.

To all whom it may concern:

Be it known that I, CORWILL JACKSON, a citizen of the United States, residing at the city and county of Kalamazoo, State of Michigan, have invented certain new and useful Improvements in Tamers, of which the following is a specification.

This invention relates to improvements in tampers.

10 My improvements are especially designed by me for embodiment in tie tampers and the embodiment illustrated is especially adapted for that purpose. My improvements are, however, of advantage and readily adapted for use in other relations.

The objects of my invention are,

First, to provide an improved tamper for use in tamping ties and the like which is highly efficient and tamps the material upwardly against the under side of the tie as well as downwardly, providing a bed therefor which is not likely to settle or have portions in which the material is easily disturbed by streams of water or the like.

25 Second, to provide an improved tamper which is of very large capacity in that it enables the performance of a large amount of work with comparatively little effort on the part of the user.

30 Third, to provide an improved tamper which is very durable in use.

Fourth, to provide an improved motor driven tamper in which the parts are simple in structure and arrangement and not likely 35 to become broken or get out of repair in use.

Further objects, and objects relating to structural details, will definitely appear from the detailed description to follow.

I accomplish the objects of my invention 40 by the devices and means described in the following specification. The invention is clearly defined and pointed out in the claims.

A structure which is a preferred embodiment of my invention is clearly illustrated in the accompanying drawing forming a part of this specification, in which:

Figure I is a side elevation of a tamper embodying the features of my invention 50 shown in operative or tamping position relative to a road bed and tie laid thereon.

Fig. II is an enlarged side elevation.

Fig. III is a detail inverted view.

Fig. IV is an enlarged detail section on

a line corresponding to line 4-4 of Figs. 55 II and V showing details of the handle connections and vibrating means.

Fig. V is an enlarged detail longitudinal section on a line corresponding to line 5-5 of Figs. III and IV showing details of the 60 vibrating means.

Fig. VI is a conventional illustration of a rail and its supporting tie shown conventionally with the end of the tamping bar of my improved machine in operative 65 relation thereto, its stroke being indicated by dotted lines in Fig. VI.

Fig. VII is a detail view partially in section on line 7-7 of Fig. II showing details of the handle connections.

In the drawing similar reference characters refer to similar parts throughout the several views, and the sectional views are taken looking in the direction of the little arrows at the ends of the section lines.

Referring to the drawing, I provide a motor shown conventionally at 1 having a shaft 2 provided with unbalancing weight or vibrating member 3. The shaft 2 is mounted in bearings 4 and 5, the bearings 80 being disposed on opposite sides of the weight 3 at the lower end of the casing. The casing is designated generally by the numeral 7. One member of the casing is provided with ears 9 connected to the clamping cross piece 10 at the upper end of motor by means of the bolts 11. On the lower end of casing I rigidly mount the tamping bar 12, the bar in the structure illustrated being secured by the U clamping bolts 13 90 which engage lugs 14 on opposite sides of the casing rigidly supporting the tamping bar at right angles or transversely of the shaft.

The yoke-like handle 15 is provided with 95 hand pieces 16 and 17. The handle has resilient or spring members 18 and 19 terminating in coils secured to the pins 20 and 21 respectively. The pin 21 is carried by an ear 22 disposed centrally on the upper 100 end of casing. The pin 20 is carried by a resilient disk 23 disposed in this ear. The pins 21 to which the spring members 19 of the lower arm of the handle are secured are carried by resilient disks 24 disposed in 105 recess-like pockets 25 located near the bottom of the casing. The cover plates 26 are mounted on the pins. The pin 20 is dis-

posed centrally at the upper end of casing while the pins 21 are disposed in alinement therewith on the sides of the casing.

Each arm of the handle is provided with 5 spring members secured to the pins, so that the handle tends to restrict vibration transversely of the casing and permits it to vibrate more freely in the longitudinal direction of the tamping bar, the result being 10 that the vibration assumes an oscillating movement centered about the upper pivot, the end of the tamping bar having an up and down as well as a forward or longitudinal movement. The result of this is that 15 in tamping a road bed as 27, the material is tamped upwardly against the bottom of the tie and the road bed compacted downwardly as well.

My improved tamper is very simple and 20 economical in structure, enables the performance of a large amount of work with little effort on the part of the operator and in a superior manner.

I have illustrated and described my 25 improvements in an embodiment which I believe very satisfactory. I have not attempted to illustrate or describe various modifications and adaptations which I contemplate as I believe the disclosure made will 30 enable those skilled in the art to which my invention relates to embody and adapt the same as may be desired.

Having thus described my invention, what I claim as new and desire to secure 35 by Letters Patent is:

1. In a tamper, the combination of a shaft having an unbalancing weight mounted at its lower end, a driving motor for said shaft, a casing provided with bearings for said 40 shaft disposed at the lower end of the casing on opposite sides of said weight, a tamping bar clamped to the lower end of said casing transversely of said shaft, a yoke-like handle each arm of which comprises spaced 45 spring members terminating in spring coils, and a pin disposed centrally at the upper end of said casing and laterally disposed pins on the sides at the lower end thereof to which the coils of said handle spring 50 members are secured, said pins being resiliently mounted on said casing, all coacting for the purpose specified.

2. In a tamper, the combination of a shaft having an unbalancing weight mounted at 55 its lower end, a driving motor for said shaft, a casing provided with bearings for said shaft disposed at the lower end of the casing on opposite sides of said weight, a tamping bar clamped to the lower end of said casing 60 transversely of said shaft, a yoke-like handle each arm of which comprises spaced spring members terminating in spring coils, and a pin disposed centrally at the upper end of said casing and laterally disposed pins on the sides at the lower end thereof 65

to which the coils of said handle spring members are secured, all coacting for the purpose specified.

3. In a tamper, the combination of a shaft having an unbalancing weight 70 mounted at its lower end, a driving motor for said shaft, a casing provided with bearings for said shaft disposed at the lower end of the casing, a tamping bar rigidly secured to the lower end of said casing transversely 75 of said shaft, and a yoke-like handle each arm of which comprises spaced spring members terminating in spring coils secured to said casing at the ends thereof.

4. In a tamper, the combination of a shaft 80 having an unbalancing weight mounted at its lower end, a driving motor for said shaft, a casing provided with bearings for said shaft disposed at the lower end of the casing, a tamping bar secured to the 85 lower end of said casing transversely of said shaft, a yoke-like handle provided with resilient connections at the ends of said casing.

5. In a tamper, the combination with a 90 shaft provided with a vibrating member, a driving motor, a casing provided with bearings for said shaft, said vibrating member being disposed at the lower end of said casing, a tamping bar rigidly mounted on the 95 lower end of said casing transversely of said shaft, and a handle comprising spring members connected at the ends of said casing to permit it to vibrate most freely in a direction longitudinally of the tamping 100 bar.

6. In a tamper, the combination with a shaft provided with a vibrating member, a driving motor, a casing provided with bearings for said shaft, a tamping bar mounted on 105 said casing transversely of said shaft, and a handle resiliently connected to said casing.

7. In a tamper, the combination with a shaft provided with a vibrating member, a 110 casing provided with bearings for said shaft, a tamping bar mounted on said casing transversely of said shaft, and a handle resiliently connected to said casing.

8. In a tamper, the combination of a 115 shaft having an unbalancing member mounted thereon, a driving motor therefor, a casing, a tamping bar rigidly mounted on said casing, and a handle having a resilient connection to said casing, so that the force 120 of the blows delivered at the end of said tamping bar is mainly in a vertical and longitudinal direction.

9. In a tamper, the combination of a shaft having an unbalancing member 125 mounted thereon, a driving motor therefor, a casing, a tamping bar rigidly mounted on said casing.

10. In a tamper, the combination of a motor, a casing, a vibrating means for said 130

casing, a tamping bar rigidly mounted on said casing, and a handle having a resilient connection to said casing.

11. In a tamper, the combination of a motor, a casing, a vibrating means for said casing and a tamping bar rigidly mounted on said casing.

12. In a tamper, the combination of a vibrating means, a tamping bar rigidly connected to said vibrating means, and a handle

having a resilient connection to said vibrating means.

In witness whereof, I have hereunto set my hand and seal in the presence of two witnesses.

CORWILL JACKSON. [L. s.]
